UNITED STATES PATENT OFFICE.

GEORG DRALLE, OF HAMBURG, GERMANY.

DESIGN FOR A CASING FOR PERFUMERY-BOTTLES.

No. 39,855:

Specification for Design.

Patented March 2, 1909.

Application filed December 18, 1908. Serial No. 468,238. Term of patent 7 years.

To all whom it may concern:

Be it known that I, GEORG DRALLE, a citizen of Germany, and a resident of Hamburg, Germany, have invented a new, original, and ornamental Design for a Casing for Perfumery-Bottles, reference being had to the accompanying drawing, forming part thereof, showing a perspective view of the casing for perfumery bottles.

I claim:

The ornamental design for a casing for perfumery bottles, as shown.

GEORG DRALLE.
